J. TIRPAK.
HOSPITAL READING STAND.
APPLICATION FILED JAN. 9, 1918.

1,286,840.

Patented Dec. 3, 1918.

UNITED STATES PATENT OFFICE.

JOHN TIRPAK, OF SOMERFIELD, PENNSYLVANIA.

HOSPITAL READING-STAND.

1,286,840.

Specification of Letters Patent.

Patented Dec. 3, 1918.

Application filed January 9, 1918. Serial No. 211,018.

To all whom it may concern:

Be it known that I, JOHN TIRPAK, a citizen of the United States of America, residing at Somerfield, in the county of Somer- 5 set and State of Pennsylvania, have invented certain new and useful Improvements in Hospital Reading-Stands, of which the following is a specification.

This invention relates to certain new and 10 useful improvements in hospital reading stands.

The primary object of the invention is the provision of a reading stand adapted as an attachment for beds and especially service- 15 able in hospitals, the arrangement being such that reading matter may be readily positioned for viewing by the occupant of the bed and the device so positioned as not to interfere in any manner with the move- 20 ments of the occupant.

A further object of the device is the provision of a reading stand adjustably mounted upon a bed for use by the occupant there- 25 of in viewing desirable objects positioned thereon, the device being readily shifted out of the way by the occupant when not desired for use and also readily readjusted when desired.

A still further object of the invention is to 30 provide a mounting stand or rack that may be readily attached to any form of bedsteads, the device being easy and inexpensive to manufacture, light in weight and pleasing in appearance.

35 In the drawing forming a part of this application and in which like designating characters refer to corresponding parts throughout the several views,

Figure 1 is a perspective view of the head 40 portion of a bed provided with the present device illustrated in its operative position.

Fig. 2 is a side elevation of the device mounted upon the headboard of the bed, the said board being shown in vertical section 45 and the device illustrated by dotted lines partially elevated to an inoperative position.

Fig. 3 is a horizontal sectional view through a portion of the head of the bed illustrating a portion of the device in top 50 plan view.

Fig. 4 is an enlarged detail horizontal sectional view of one corner portion of the device, and

55 Fig. 5 is an elevational view of a similar corner portion thereof showing the adjust-

ing member mounted upon the rail of a metal bed.

My device is adapted for employment as a reading stand with any form of bed and is herein illustrated in connection with a bed 60 10 having sides 11 and a head member 12, my improved stand 13 being adjustably mounted upon a panel 14 of the head 12 by means of a plurality of brackets 15.

The stand 13 comprises a board or plate 65 16 with a bottom ledge or flange 17 thereon adapted for holding reading matter or pictures, a retaining marginal rib 18 being provided for the said flange and a frame or extension 19 being arranged upon the top 70 of the plate 16 for assisting in supporting the articles carried by the stand.

Side arms 20 perpendicularly project from the opposite ends of the flange 17 and are arranged with forks 21 at their free ends 75 pivoted by means of bolts 22 to the brackets 15 carried by the panel 14 as heretofore noted.

Each bracket 15 consists of a strip 23 having screws 24 extending therethrough into 80 the panel 14 while a hook-shaped rack 25 centrally projecting from the strip 23 has the pivot bolt 22 mounted adjacent the base thereof while the main portion of the rack which is provided with the teeth 26 is ar- 85 ranged within the fork 21 of the adjacent arm 20.

A spring pressed catch 27 is pivoted to the lower side of each arm 20 adapted for normally engaging the rack teeth 26, thereby 90 maintaining the holding member 16 at the desired vertical adjustment relatively of the pillow 28 arranged upon the bed 10 adapted for the accommodation of the occupant thereof. 95

When a person is lying upon the bed 10 reclining upon the pillow 28, the board 16 may be arranged directly in front of the occupant as best illustrated in Fig. 1 of the drawing so that any articles upon the rack 13 will be readily viewable and accessible by such occupant. The brackets 15 are arranged adjacent the opposite sides of the head 12 of the bed so that the device does not interfere with the movements of the 105 occupant thereof it being noted that the brackets are also arranged adjacent the top of the head board 12. The occupant may readily push upwardly on the rack 13 positioning the latter as indicated by dotted 110

2
lines in Fig. 2 thereof and at which times the catches 27 ratchet over the teeth 26 for retaining the rack 13 in its desired adjusted position with the arms 20 either horizontally arranged or upwardly or downwardly inclined as found desirable. When the rack 13 is elevated, the free end portions 29 of the catches 27 may be pressed for releasing the catches when desired and permitting the rack 13 to be moved downwardly in close proximity to the bed 10 while the rack 13 may be positioned upon the bed if desired when the catches 27 have passed the lowermost teeth 26, as the bracket hooks 25 presented no obstruction for preventing the arms 20 from engaging the head 12 of the bed.

The device may be attached to the head member of a metal bedstead by employing brackets 15' of the form illustrated in Fig. 5 of the drawing and in which a shank or bolt 30 is carried by the said bracket for projecting horizontally through the top tubular rail 31 of the bedstead and retained thereon by means of a set nut 32. The remaining portions of the bracket are the same as the heretofore described and consisting of the hooked rack 25 for mounting the fork 21 of the adjacent arm 20 thereon by means of the bolt 22 and employing the spring pressed catch 27 for maintaining the arm in desired adjustment by engaging the teeth 26 of the said rack. A serviceable adjustable reading stand or rack is arranged for the comfort and accommodation of patients re-

clining upon a bed and the same is readily positioned entirely out of the way when desired, it being seen that when the catch 27 leaves the teeth 26 and passes over the upper curved end 33 of the hook 25, the catch will retain the adjacent arm 20 substantially vertically arranged.

What I claim as new is:—

An adjustable reading stand for beds comprising, in combination with the head member of a bed, a pair of spaced horizontally aligned vertically disposed hooks rigidly secured to said head member adjacent the upper corners thereof to project therefrom in a direction toward the foot member of said bed and having teeth upon their forward edges, forks spanning said hooks and pivoted to the base portions thereof adjacent said head member for vertical swinging movement, a pair of straight parallel arms rigidly carried by said forks and adapted to assume a downwardly inclined operative position, spring catches upon said arms arranged to ratchetingly engage the teeth of said hooks, a plate having a bottom flange and perpendicularly rigidly carried by and extending between the forward free ends of said arms, a longitudinal marginal retaining rib upon the upper face of said plate flange, and a rigid supporting frame upon the top edge of said plate substantially as 60 and for the purpose described.

In testimony whereof I affix my signature.
JOHN TIRPAK.
